CHARLES R. MILLER.

334 A. L. Jackson Attorney

UNITED STATES PATENT OFFICE.

CHARLES R. MILLER, OF COLLINSVILLE, TEXAS, ASSIGNOR OF ONE-HALF TO C. W. FELLOWS, R. L. GOUGHENHEIM, C. B. MEADOWS, AND J. M. MEADOWS, ALL OF HOUSTON, TEXAS.

ICE-SCORING MACHINE.

Application filed October 30, 1922. Serial No. 598,046.

To all whom it may concern:

Be it known that I, CHARLES R. MILLER, a citizen of the United States, residing at Collinsville, in the county of Grayson and State 5 of Texas, have invented certain new and useful Improvements in Ice-Scoring Machines, of which the following is a specification.

My invention relates to ice scoring machines and particularly to scoring machines 10 for scoring blocks to meet requirements of the laws relative to weights and measures; and the object is to provide machines which will score every block of ice accurately, to provide machines which are simple in operation, and to provide machines in which most 15 of the parts operate automatically and with speed. The advantage of the improved machine is that will score the ice vertically and horizontally, changing from vertical scoring to horizontal scoring automatically and moving or shifting the ice blocks automatically. Other objects and advantages will be fully explained in the following description and the invention will be 20 more particularly pointed out in the claims.

Reference is had to the accompanying drawings which form a part of this application.

Fig. 1 is a side elevation of the machine. 30 Fig. 2 is a plan view of the same. Fig. 3 is a detail view of the ratchet shown in Fig. 2. Fig. 4 is a detail view of the discharge chute, showing the springs for centrally positioning the blocks of ice therein.

Similar characters of reference are used 35 to indicate the same parts throughout the several views.

The machine is provided with pairs of upright frame members 1, 2, 3, 4, and 5 which 40 support the machine. An additional support consists of a slab 6 which is positioned at an incline. The frame members 3, 4, and 5 are also positioned at inclines. The slab 6 serves to support the side frame members 45 7 and the bars 8 which form the bottom of the ice chute for discharging the blocks of ice. The machine is composed of two members,—the member on the right side of the drawings being the elevating member and the 50 member on the left side of the drawings being the discharge member. The discharge member has a pair of side beams 9 intermediate the upper and lower sides of the machine attached to the upright members 1 and 2. Two longitudinal beams 10 and 11 are

common to both the elevating member and the discharge member of the machine and are attached to the uprights 1 to 5 inclusive. These beams are offset outwardly at 12 to provide for mounting the ice elevator and other working parts hereinafter described. The machine is further provided with pairs 60 of cross beams 13. The elevating member is provided with two longitudinal frame members 14 which are attached to the uprights 65 3 and 5. An ice elevator frame 15 is provided and consists of a rectangular structure, having end bars 16 and longitudinal bars 17 attached rigidly together. The elevator is movable vertically at an incline on 70 the inside of the pairs of uprights 3, 4, and 5 which are inclined.

The machine is provided with a power shaft 18 and a power pulley 19 rigid therewith to be driven by any suitable power. 75 This shaft 18 is driven constantly during operation and operates all other working parts. The shaft 18 is journaled in bearings 20 which are attached to the beams 10 and 11. Beveled gear wheels 21 are rigid with shaft 18 and these wheels drive the beveled gear wheels 22 which are rigid with the vertical shafts 23 which are journaled in bearings 24 which are attached to the longitudinal beams 7 and 10. Circular saws 25 are 80 rigid with the shafts 23 for scoring the blocks of ice on the sides or horizontally as the blocks of ice are being discharged down the ice chute.

Beveled gear wheels 26 are rigid with the 85 shafts 23 and serve to drive beveled gear wheels 27 which are rigid with shafts 28 which are journaled in bearings 29 which are attached to the longitudinal beams 7 and 90 in bearings 30 which are attached to the upright beams or supports 5. The shafts 28 are provided with circular saws 31 which score the ice blocks vertically as the blocks are being elevated by the elevator 15. The elevator 15 is provided with spring guide 95 rods 32 which serve to hold the ice blocks centrally positioned while they are being elevated. It will be understood that such guide rods are on both sides of the elevator. The inclined position of the elevator 15 and 100 the guide frame members therefor serve to keep the ice blocks in the forward position against the guide slab 6.

The elevator 15 is raised by chains 33 which are attached to the elevator and to 110

drums 34 which are rigid with shafts 35 which are journaled in bearings 36 which are attached to the frame members 10 and 11. Means for driving the shafts 35 are provided. A shaft 37 is journaled in bearings 38 which are attached to the off-set portions 39 of the beams 10 and 11. The shaft 37 is driven from the shaft 18 by means of a power transmitting pulley 40, belt 41 which is crossed and which runs on and drives the fast pulley 42 on shaft 37. A pinion 43 is rigid with shaft 37 and meshes with and drives a cog wheel 44 which is rigid with shaft 45 which is journaled in bearings 46 which are attached to the off-set portions 39 of the beams 10 and 11. A pinion 47 is rigid with shaft 45 and meshes with and drives a cog wheel 48 which is loosely mounted on shaft 49 which is journaled in bearings 50 which are attached to beams 10 and 11. The wheel 48 has one member of a clutch 51 integral therewith. The wheel 48 is locked to the shaft 49 for driving purposes by the other member 52 of the clutch 51 which is key-seated and slidable on the shaft 49. Beveled gear wheels 53 are rigid with shaft 49 and mesh with and drive beveled gear wheels 54 which are rigid with shafts 35. The clutch members 51 and 52 are thrown in and out of mesh by a bell-crank lever 55 which is fulcrumed on beam 11. A spring 56 is attached to the beam 11 and to the lever 55 and holds the clutch members in mesh. When power is applied to shaft 37 by the gearing above described including the fast pulley 42, the elevator 15 is moved upwardly and the gearing continues to run until the clutch members 51 and 52 are thrown out of mesh. The unmeshing of the clutch members is accomplished automatically by the movement of a block of ice. A trip 57 is suspended in the path of the ice by a shaft 58 which is journaled in bearings 59 which are attached to beams 10 and 11. A crank 59' is rigid with shaft 58. A rod 60 is pivotally connected to the crank 59 and connected to the lever 55. When a block of ice slides down the ice chute on beams 8, it will strike the trip 57 and this will actuate the lever 55 to unmesh the clutch members 51 and 52 so that the elevator gearing will be released. The weight of the elevator will reverse the gearing and let the chains 33 unwind from drums 34 and let the elevator 15 go back down to starting position. Prior to this operation, the elevator gearing has been stopped from running. Guide members 61 are attached to the elevator 15 and slide against the upright members 3 and 5 to hold the blocks of ice against wobbling or shaking. The guide members 61 at the entrance end of the machine receive the block of ice and one of the guides 61 serves as a tripping means for a belt shifter. A trip 62 is mounted on a rocker-shaft 63 which is journaled in

bearings 64 which are attached to the frame members 4 and 5. The shaft 62 is provided with a crank 65 for manual operation for shifting the belt for commencing operations. The shaft 63 is also provided with a crank 66. The belt shifter consists of a bar 67 which is slidable axially in bearings 68 which are attached to beams 10 and 11 and which carries a loop or hook 69 for engaging the belt 41. The end of the crank 66 projects loosely through the end of the bar 67 which has an off-set portion for this purpose. When the guide member 61 strikes the trip 62, the belt shifter will throw the belt 41 from the fast pulley 42 to the loose pulley 70, so that the elevator gearing will stop running. A ratchet 71 on shaft 37 prevents the shaft 37 from turning backwardly.

The machine is set at an incline so that no additional mechanism will be required after the blocks of ice have been scored vertically in order to score the blocks horizontally. In operation, after the gearing has been set in motion and after the belt 41 has been shifted to the fast pulley 42 by manually actuating the crank 65, the block of ice 74 having been placed on the elevator 15 through the entrance end of the machine, the block of ice 74 will be elevated and simultaneously the saws 31 will score the block of ice on both sides vertically. Prior to the starting of the ice block down the discharge chute, the trip 62 will be actuated by the guide member 61 and the belt shifter will shift the belt 41 to the loose pulley 70 and stop the elevator gearing from running. As soon as the block of ice is elevated high enough, sliding against the slab 6, so that the bottom of the block of ice can pass onto the chute 8, the block of ice will move automatically down the chute 8. Springs 73 may be attached to the uprights 7 to aid in starting the blocks of ice onto the chute 8. As the block of ice passes down the discharge chute, the saws 25 will score the block horizontally or on the sides of the block. The blocks of ice are scored in one direction while the blocks are moving upwardly and scored in the opposite direction while the blocks are going down the chute 8.

The trip 57 and the spring 56 perform another function. The function above set forth was to let the elevator go back to starting position. The additional function of the spring 56 acting on the trip 57 will retard the speed of the ice block and prevent the block from going too fast for the scoring operation by the saws 25. The tension of the spring 56 may be regulated as required.

At times there may be portions or bumps of ice frozen on the sides of the blocks of ice. In order that such portions of ice may not hinder the operation of the ice blocks passing through the discharge chute, the

side members 7 may be spaced far enough apart and springs 72 attached to the inside so that the springs will hold the blocks of ice centrally positioned and in case of bumps 5 on the sides of the ice blocks, the springs will yield and let the blocks pass.

What I claim, is—

1. An ice scoring machine comprising an elevating member and an inclined discharge 10 member in alignment therewith, an elevator and scoring means in said elevating member, gearing for operating said elevator and said scoring means simultaneously, said elevating member and said discharge member being positioned for discharging blocks 15 of ice automatically immediately and directly after said elevating and scoring, and means for scoring blocks of ice horizontally while passing by gravity through said discharge member.

2. An ice scoring machine comprising an elevating member and an inclined discharge member in alignment therewith, an elevator and scoring means in said elevating member, gearing for operating said elevator and gearing for operating said scoring means simultaneously, means for automatically stopping the elevating gearing at the moment said elevator reaches its upper limit 25 actuated by said elevator, said elevating and discharge members being positioned for immediately and directly discharging blocks of ice automatically after said elevating and scoring, and means for scoring blocks 30 of ice while passing by gravity through said discharge member.

3. An ice scoring machine comprising an elevating member and an inclined discharge member in alignment therewith, an elevator 40 and scoring means in said elevating member, gearing for operating said elevator and gearing for operating said scoring means simultaneously, means actuated by said elevator for automatically stopping said elevator 45 gearing at the moment said elevator reaches its upper limit, said elevating and discharge members being positioned for immediately and directly discharging blocks of ice automatically after said elevating and scoring, means for scoring blocks of ice 50 while passing through said discharge member, and means operatively connected with said gearing automatically actuated by blocks of ice passing through said discharge 55 member for releasing said elevator to permit the elevator to go back to starting position.

4. An ice scoring machine comprising an

elevator chute and an elevator adapted to be moved in said chute and an inclined discharge chute at right angles to said elevator chute and forming a continuous passage for blocks of ice therethrough, said chutes being inclined for causing blocks of ice to be discharged automatically by gravity from said elevator chute through said discharge chute, means for elevating blocks of ice in said elevator chute and simultaneously scoring the ice in one direction, and means for scoring the ice at right angles to the first scoring 70 while passing through said discharge chute.

5. An ice scoring machine comprising an elevator chute and an elevator for operation therein and an inclined discharge chute at right angles to said elevator chute and forming a continuous passage for blocks of ice therethrough, said chutes being inclined for causing blocks of ice to be discharged automatically by gravity from said elevator chute through said discharge chute, means 80 for elevating blocks of ice in said elevator chute and simultaneously scoring the ice in one direction, means for scoring the blocks of ice at right angles to the first scoring 85 while passing through said discharge chute, and means for retarding the blocks of ice while passing through said discharge chute.

6. An ice scoring machine comprising an inclined elevator chute and an inclined discharge chute at right angles thereto and forming a continuous passage for blocks of ice therethrough, means for elevating blocks of ice in said elevator chute for starting the same through said discharge chute and simultaneously scoring the ice during 95 the elevation thereof, yielding means for holding the blocks of ice centrally positioned in said discharge chute while passing therethrough, and means for scoring the ice at right angles to the first scoring while passing through said discharge chute.

7. An ice scoring machine comprising an inclined elevator chute and an inclined discharge chute at right angles thereto and forming a continuous passage for blocks of ice therethrough, means for elevating blocks of ice in said elevator chute for starting the same directly through said discharge chute and simultaneously scoring the ice during 105 the elevation thereof, and means for scoring the ice at right angles to the first scoring while passing through said discharging chute.

In testimony whereof I set my hand this 26th day of October, 1922.

CHARLES R. MILLER.
